UNITED STATES PATENT OFFICE.

JAMES BADLAT, OF DES MOINES, IOWA.

SHOE-DRYING ATTACHMENT FOR SOLE-SEWING MACHINES.

1,320,665.

Specification of Letters Patent.

Patented Nov. 4, 1919.

Application filed September 4, 1917. Serial No. 189,496.

To all whom it may concern:

Be it known that I, JAMES BADLAT, a citizen of the United States, and resident of Des Moines, in the county of Polk and State 5 of Iowa, have invented a certain new and useful Shoe-Drying Attachment for Sole-Sewing Machines, of which the following is a specification.

The object of my invention is to provide 10 a shoe drying attachment for soling machines of simple, durable and inexpensive construction.

A further object of my device is to provide 15 a drying rack adapted to be operated by the steam generated from the steam generator of sole sewing machines. In this connection it should be mentioned that the sole sewing machines, which are in common use in repair shops are provided with steam 20 generators, which are connected with the waxing device in the machine, so that the wax may be kept warm and in a semi-fluid condition to properly wax thread sewed through the soles. It should also be explained that it is the custom to "temper" 25 leather, which is formed into the half soles, which are used for repairing. This tempering process consists of soaking the leather in water, so that it becomes sufficiently pliable to be readily handled in the process of 30 half soling shoes. When, however, the leather becomes so soaked it is desired to finish off the edge of the sole and to black the edge, it is found that the wet 35 leather has a tendency to fray, so that it is impossible to put a smooth hard finish on the edge of it when one attempts to finish the edge of the sole, while it is still damp.

A further disadvantage results from the 40 attempts to finish the edge of the sole during the time that it is still damp in that the damp leather damages the sand paper, which is used for buffers, so that almost three times as much sand paper is worn out where 45 the buffers are used with the damp leather as is the case where the buffers are used with dry leather. My invention, therefore, consists of providing means for drying the soles rapidly and conveniently as they are finished 50 by the sole sewing machine, so that by the time that the operator is ready to proceed with the edge finishing process the sole may be sufficiently dry to admit a smooth finish without excessive wear on the sand paper 55 of the buffers.

A further object of my invention is to

provide a steam coil having a drying rack disposed thereabove and to connect the steam coil with the steam pipes of the wax heating system of the sewing machine whereby the drying rack may be operated without additional expense. 60

With these and other objects in view, my invention consists in the construction, arrangement and combination of the various 65 parts of my device whereby the objects contemplated are attained, as hereinafter more fully set forth, pointed out in my claims, and illustrated in the accompanying drawings, in which:

Figure 1 shows a side elevation of my improved drying rack and its connections with the sole sewing machine and generator the outline of the former being shown in light 70 lines, and

Fig. 2 is a top or plan view of the drying rack itself.

Referring to the accompanying drawings, I have used the reference numeral 10 to indicate generally the base of a sole sewing machine having the sewing mechanism indicated generally by the numeral 11. A steam generator 12 is provided as a part of the equipment of this machine and is operatively connected with the wax heating portions thereof by the pipes 13 and 14. 80

My invention consists in connecting to 85 these pipes 13 and 14 a steam drying rack, which is so placed that the shoes, which have been passed through the machine 11 may be 90 conveniently thrown upon the drying rack to be dried while other shoes are being operated upon by the machine 11. The cross slats 21 and the longitudinal slats 20 must be formed from some non-conducting ma-

terial such as wood in order that the leather may not become burnt from the heat from the coil. Experience has shown that warmed metal will burn the leather very much more quickly than will wood or similar material, which does not conduct the heat readily, so that the drying frame should be composed of such a non-conducting material and so shaped that shoes thrown thereupon will not be burned and 95 the life thereby taken from the leather. 100

My drying rack consists of a base 15, which as shown is secured to the floor by a floor flange 16 and having at its upper end a second floor flange 17. A U-shaped strap 110 iron member 18 has its central portion secured to the floor flange 17 and its ends

turned upwardly. The ends of the member 18 support a horizontal drying rack 19, which consists of longitudinal slats 20 between which extend a plurality of spaced parallel cross slats 21. A steam coil, which rests upon the central portion of the member 18, consists of a plurality of spaced parallel steam conducting pipes 22, which are suitably connected together at their ends 10 by means of elbows 23. A supply pipe 24 for the steam coil is connected by an elbow 25 in which a T 26 is inserted in the supply pipe 14 for the machine 11. A return pipe 27 of the steam coil is connected into the 15 return pipe 13 of the machine 11.

In the practical operation of my improved device the steam coil is connected to the generator 12 in the manner indicated in the drawing and hereinbefore described and the drying rack is installed to the right of and in line with the machine 11, so that as soon as the soles have been sewed to the 20 shoes on the machine 11, the shoe may be thrown onto the rack where it will be dried from heat of the steam coil. It may be suggested in this connection that experience 25 has demonstrated that the heat of approximately 125 degrees is best suited for the drying of the shoe leather as at this heat there is no tendency to burn the leather and yet a sufficient heat is produced to cause the moisture therein to evaporate. The coils herein disclosed are substantially of such size relative to the capacity of the generator 30 that they will permit very closely the desired degree of heat but in order to insure this result I have provided a control valve 28, which is disposed in the supply pipe 25 of the steam coil.

By this means the heat supplied by the drying rack may be accurately gaged. It may be suggested that the further advantage resides from this particular heat that the drying rack does not furnish sufficient heat 45 to materially change the temperature of the room in which it may be installed, although it furnishes sufficient heat to dry the sole of shoe enough, so that it may be finished on the finishing machine while the sole of the 50 other shoe is being sewed on the sewing machine. The sole of the second shoe may then be dried on the drying rack while the first shoe is being put through the finishing process, so that there is no necessity for delay 55 due to the drying of the soles upon my drying rack, and so that they may be nicely finished at their edges without undue wear on the sand paper of the buffers. It should also be suggested that my improved drying

rack may be installed at a very slight cost 60 and there is no operating expense connected therewith under ordinary circumstances, as the steam generator of the sole sewing machine does not cost any more to run when operating the drying rack than when its 65 steam is merely directed into the wax heating mechanism of a sewing machine.

I claim as my invention:

1. In a device of the class described adapted to be connected into the steam heating 70 system of a shoe sole sewing machine, a drying rack comprising a vertical upright, a fitting at the lower end thereof adapted to be secured to a floor, a fitting at the upper end of the upright, a U-shaped member having its central portion secured to the fitting and its end portions extended upwardly to form supports, a pair of horizontally aligned spaced parallel slats mounted on the said end portions, a plurality of spaced parallel 75 cross slats being composed of material which does not conduct heat, a plurality of spaced parallel tubes of heat conducting material communicating with each other and supported by the central portion of the U shaped member in position spaced a predetermined 80 distance below the cross slats, and means for operatively connecting said tubes with the heating system of the sewing machines.

2. In a device of the class described adapted to be connected into the steam heating 90 system of a shoe sole sewing machine, a drying rack comprising a vertical upright, a fitting at the lower end thereof adapted to be secured to a floor, a fitting at the upper end of the upright, a U shaped member having its central portion secured to the fitting and its end portions extended upwardly to form supports, a pair of horizontally aligned spaced parallel slats mounted on the said end 95 portions, a plurality of spaced parallel cross slats extended between the first slats, said last described slats being composed of material which does not conduct heat, a plurality of spaced parallel tubes of heat conducting 100 material communicating with each other and supported by the central portion of the U shaped member in position spaced a predetermined distance below the cross slats, a supply pipe connected to one of said tubes, 110 a return pipe connected to another of the tubes, means for operatively connecting said pipes with the heating system of the sewing machine, and means for controlling the supply of heat through the supply pipe. 115

Des Moines, Iowa, August 25, 1917.

JAMES BADLAT.
